REFRIGERATING APPARATUS

William W. Higham, Marion, Ohio, assignor to
 Newport Steel Corporation, a corporation of
 Indiana

Application March 5, 1946, Serial No. 652,027

3 Claims. (Cl. 230—206)

1

This invention relates to refrigeration and has particularly to do with a refrigerant compressor of the type commonly known as a "sealed type" of compressor wherein the driving electrical motor and the compressor are mounted within a sealed chamber or casing.

Some of the features incorporated herein are embodied in the refrigerating unit disclosed in my co-pending application Serial No. 652,026, filed March 5, 1946. The unit disclosed herein however is a larger unit in which there are provided a plurality of compressor cylinders. In some respects the disclosure herein relates to an improved construction in which the design is simplified and a minimum number of parts are required.

One of the objects of my invention as disclosed herein is therefore the provision of a refrigerating unit of the "sealed type" incorporating a plurality of compressor cylinders and having a minimum number of parts and improved construction.

A further object of my invention as disclosed herein is the provision of a unitary casting including a plurality of compressor cylinders having an integral muffler-manifold chamber positioned between the cylinders.

A further object of my invention is the provision of improved heat exchange arrangement by which a thermostat control for preventing overheating of the motor is provided.

A further object of my invention is the provision of improved arrangements for heat exchange between the refrigerant and the motor for cooling the motor.

One of the features of my invention is the provision of a "sealed type" refrigeration unit which includes a casing which is substantially symmetrical about a vertical axis and which has a rotating shaft positioned substantially on said vertical axis.

A further feature of my invention is the provision of a single casting which serves as a motor support, provides a bearing for the rotating shaft, and provides the compressor cylinders and muffler manifold.

A further feature of the invention is the provision of counter-balance weights for balancing the off-set portions of the vertical shaft so as to simplify and shorten the structure and enclose the whole unit within a minimum space.

A further feature of my invention is the provision of passages around the motor and between the motor and the casing insuring a passage for

2

expanded refrigerant in heat exchange relationship with the motor.

A further feature of my invention is a provision of a shoulder on the casing for the insertion of the electrical plug connections and for the inlet and outlet openings or fittings for the expanded and compressed refrigerant.

Further objects and features will appear from the following description when considered in connection with the accompanying drawings wherein a preferred form of embodiment of the invention is shown.

In the drawings:

Fig. 1 is a view in elevation of the unit showing the exterior of the casing;

Fig. 2 is a top plan view of the refrigerating unit;

Fig. 3 is a view in section on an enlarged scale taken substantially on the line 3—3 of Fig. 2;

Fig. 4 is a bottom plan view on an enlarged scale having the bottom portion of the casing removed so as to show the mechanism within the shell;

Fig. 5 is a view in section on a still larger scale taken substantially on the line 5—5 of Fig. 2;

Fig. 6 is a view similar to Fig. 1 showing the casing in elevation and showing the unit from a different angle and the resilient mounting thereof;

Fig. 7 is a view in section taken substantially on the line 7—7 of Fig. 3 and showing the pump structure; and

Fig. 8 is a fragmentary view in section taken substantially on the line 8—8 of Fig. 4.

Referring in detail to the drawings wherein there is illustrated one embodiment of my invention and in particular to Figures 1, 2 and 3 thereof, it may be seen that my improved refrigerating unit comprises an outer casing 11, a motor unit

12, compressor cylinders 13 and 14 (shown in Figures 3 and 4) and a muffler-manifold element 15. Suitable inlet and outlet connections for the expanded and compressed refrigerant are provided as are a lubricating system for lubricating the entire unit, electrical connections therefor and a resilient mounting for the unit, each of which parts will be now described in detail.

Referring especially to Figure 3, it may be seen that the casing 11 is an exterior shell which may be preferably formed from sheet metal, the lower portion thereof being in the form of a cylinder closed at one end and having a peripheral wall 16 and a bottom wall 17. The upper portion is also cylindrical in the main and has an end or upper wall 18 and a cylindrical side wall 19 of

smaller diameter than the diameter of the cylindrical wall 16. The side wall 19, however, is enlarged to provide a flaring circumferentially extending shoulder 21 and provided with an enlarged circumferential flange 22 telescoping over the peripheral wall 16 of the lower portion. The flange 22 and the upper part of the peripheral wall 16 of the lower portion are weld united as at 23. The upper and lower portions of casing 11 thus are joined to provide a casing which is substantially symmetrical with respect to the central vertical axis thereof as seen in Figs. 1 and 2.

The end wall 18 of the upper portion is provided with a depression 24 within which there is disposed a mass of non-resonant material 25. This material is protected from extraneous oil or dirt by a covering plate 26 secured to the end wall by a stud 27 which may if desired be welded to the end wall 18. The covering plate 26 holds the material under some compression and provides a smooth exterior contour. This construction absorbs and deadens vibrations by the absorption thereof by the non-resonant material 25.

The refrigerating unit 11 may preferably be spring mounted and for this purpose a plurality of brackets 28 are provided as is shown in Figures 1, 2 and 6. These brackets are mounted on the outside of the casing and are arranged to be supported by springs such as 29. Bolts 31 may pass through the brackets 28 and the springs 29 and secure the unit to any suitable support such as the supports shown at 32.

In order to simplify the construction, minimize the space required, and improve the construction in general by way of decreasing cost, improving rigidity, etc., I provide within the casing a single casting 33 which serves as a support for the motor, provides a bearing for the rotating shaft, forms the cylinders of the compressor, and provides a chamber which serves as a muffler and manifold for the compressed gases. Thus, the casting 33 has an upper portion 34, an intermediate spider portion 35, a cylinder portion 36, as well as a bottom bearing portion 37. Each of these portions will be referred to later in describing the various functional units associated with them. The upper portion of the casting is firmly secured within the inside of the upper part of the shell. Thus it may be seen that the upper portion 34 fits snugly within the cylindrical portion 19 of the upper part of the casing and is secured by a press fit. It may be secured thereto in any other suitable manner.

The driving motor 12 includes a stator portion comprising a stationary mounting 39 and motor windings 41. The mounting 39 is secured within the upper portion 34 of the main casting 33 which portion 34 thus forms a part of the motor. Rotatively mounted within the stator is the rotor or armature 42. The armature 42 is provided with a pair of weights 43 and 44 arranged to counter-balance the off-set weight of the crank shaft as will be later described.

The motor drives a shaft 46 which is disposed in the vertical axis of the unit which is arranged substantially concentric about said vertical axis. Thus the cylindrical portions 16 and 19 of the casing 11 are concentric about said axis and the main casting 33 except for the cylinders 13 and 14 and the unit 15 is substantially concentric about such axis. The shaft 46 is mounted in bearings 47 and 48. The bearing 47 is secured by cap screws 49 to the intermediate spider portion 35 of the main casting. The bearing 48 is formed

as an integral part of the lowermost portion 37 of the main casting. The shaft 46 is provided with a crank throw 51 to which are connected cranks (such as the crank 54) for the pistons of the cylinders 13 and 14.

The compressor cylinders 13 and 14 are substantially similar and description of one will suffice for both. As shown in Figure 3 the cylinder 13 is formed integrally as a part of the casting 33 within the cylinder portion 36 thereof. It provides an operating chamber 52 in which there is positioned a piston 53 connected to the crank 54 by a hollow wrist pin 55 held against axial movement by a spring clip 56. An inlet valve 57 is provided for at times connecting the working chamber 52 with an inlet recess 58 and an outlet valve 59 is provided for at times connecting the working chamber 52 with an outlet recess 61. The crank throw 51 is connected to both of the connecting rods for both of the cylinders 13 and 14.

Referring again to Figure 4, it may be seen that the cylinder portion 36 of the casting 33 has formed integrally therewith intermediate the cylinders 13 and 14 a muffler or manifold 15. The interior of this muffler or manifold is connected by passages formed within the casting 33 itself with the outlet recesses 61 of the compressor cylinders 13 and 14. Thus the refrigerating gases are compressed by the action of the compressors 13 and 14 and forced through the recesses 61 to the manifold-muffler 15 whereby the compressed gases flow together before being forced outside of the sealed unit and whereby the noise of the compressors is minimized.

As stated above, the refrigerating unit is a part of a compressor-condenser-expander refrigerating system. Expanded refrigerating gases coming from the expander which is outside of the system flow into the casing through the inlet plug 62 and fill the interior of the casing above the level of the oil which level is shown at 63 in Figure 8. From the interior of the casing (referring to Figure 3), the expanded gases are forced upward through the motor 12 and are then drawn down through passages 64 formed in the upper part 34 of the casting 33. Thus the gases are twice brought into heat exchange relationship with the motor 12 and cool both the rotor element and the stator element thereof. From the passages 64, the expanded gases pass by means of tubes 65 to the inlet recesses 58 of each of the compressor units 13 and 14. As stated above, the refrigerating gases, after being compressed by the compressors 13 and 14, are forced to the manifold 15. From the manifold 15 they pass by means of the outlet tube 66 to the outlet plug 67. The outlet tube 66 is formed with a coil 68 below the manifold and this coil 68 is immersed in the lubricating oil which fills the bottom portion of the casing.

I provide a construction in which all openings into the casing are formed in the shoulder 21.

Referring again to Figure 8 which shows more in detail the structure of the parts comprising the inlet for expanded gases associated with the plug 62, it may be seen that the plug 62 is sealed within the shoulder 21 as by a gasket 69 and is thus connected to a tube 71 secured to and extending downward to a point within a concentric larger diameter sleeve 73 which is perforated so that the expanded gases may pass into the interior 20 of the casing 11. The sleeve 73 is secured to the tube 71 and the upper end thereof is sealed by suitable means such as that shown

at 15. Thus I insure that any condensed portion of the expanded refrigerant is boiled to a gas by the warm lubricant. On the other hand, the loop 68 of the tube 66 in passing through the lubricant has removed therefrom a portion of the heat of compression and the lubricant is warmed thereby. The incoming expanded gases in passing upward through the motor and downward through passages 64 (being cooler than the heated motor) aid in keeping the motor cool. Not only do the 10 gas inlet and the gas outlet as explained above extend through the shoulder 21, but also as substantially explained the electrical connections also all are positioned to extend through the shoulder.

I provide means by which the lubricant normally maintained in the lower portion of the casing is circulated through the bearings 47 and 48 under pressure. Referring to Figure 7, it may be seen that the lower portion of the shaft 46 is provided with a transverse slot 76 in which there is positioned a slideable vane 77. As shown in Figure 3, the lower end of the shaft 46 rests on a plate 10 which is formed with a port 78. Lubricant drawn in through the port 78 is forced by rotation of the opposite ends of the vane 77 through an outlet port 79, a radial passageway 81, an axial passageway 82 and various circumferential grooves 83 and 84 to the bearings 47 and 48. It is forced out through radial passageways 85 and 86 to lubricate the connecting rods 54 and through a passageway 87 to lubricate the wrist pins 55 and the interior of the cylinders 13 and 14. The tubes 65 have loose fits in the heads of the cylinders 13 and 14 and oil entering around the tubes lubricates the valves 57 and 59. Additional details of the lubricating system and lubricating pump are disclosed in my co-pending application Serial No. 652,026, filed March 5, 1946, referred to above wherein the inventions involved in said lubricating pump and lubricating system are claimed.

The electrical control for my improved refrigerating unit may be seen from a consideration of Figures 3, 4 and 5. A unit control assembly 101 is mounted at one side on the cylindrical portion 19 and extends down over a portion of the shoulder 21 of the upper portion of the casing 11 and is provided with a cover 102. Extending through the cover 102 is an electrical inlet conduit 103 from which three electrical leads 104, 105, and 106 extend. Within the cover 102 and extending through the shoulder 21 are three electric plugs 107, 108 and 109. These plugs pass through a gas tight sealed packing in the shoulder as is shown at 111. The electrical lead 104 is connected to a thermostat 112 which is in turn connected to the plug 107 by an electrical lead 113. The thermostat 112 is so arranged that the electrical circuit is broken either by excessive heat or by overload of electrical demand or a combination of a lower high heat and a lesser overload. The electrical leads 105 and 106 are connected to the plugs 108 and 109, respectively. Within the casing 11 (see Figure 4) the plugs 107, 108 and 109 are respectively connected by leads 114, 115 and 116 to the motor windings. As may be understood, the lead 116 is the main lead, the lead 115 is the starting lead and the lead 114 is the common lead. Thus it may be seen that the refrigerant inlet 62, the refrigerant outlet 67, and the plugs 107, 108 and 109 all extend through the shoulder 21. The only openings into the sealed casing are formed in the upper portion of the casing, and in fact the only openings are in the shoulder 21 thereof.

As may be clearly seen in Figures 3 and 5, the 75

thermostat 112 is in close contact with the portion 19 of the casing which is in thermal contact with the cylindrical support portion 34 of the casting. The support portion 34 is in fact a part of the motor unit and thus an overheating of the motor is promptly transmitted to thermostat 112 and the electrical circuit is thereby broken and the motor is stopped.

It is believed that the operation of my improved refrigerating unit will be clear from the above. In general, expanded refrigerant flows from an expander not shown, into the interior 20 of the casing 11 through inlet 62, tube 71, sleeve and screen 73. Thence it is sucked upward through the motor and downward through the passages 64, the tubes 65, the recesses 58, and the chambers 52 by the compressor units 13 and 14. The compression strokes of the compressors 13 and 14 compress the gases and force them out through recesses 61 to muffler-manifold 15 from which they pass by tube 66 to outlet 67. From the outlet 67 the compressed gases pass to a condenser (not shown) and thence to the evaporator (also not shown).

25 In moving through the passages in and around the motor, the expanded gases aid in keeping the motor 12 cool. The compressed gases have part of their heat of compression removed by their passage through the loop 68 of the tube 66 inasmuch as that loop dips into the lubricant in the bottom of the casing.

The various bearing surfaces are lubricated by oil pumped thereto by the oil pump formed by the shaft 46, the vane 76 and the chamber 80.

30 The electric current is supplied through the unit 101 and the unit as a whole is guarded against overheating by the thermostat 112. The whole unit is resiliently mounted on springs 29.

It is to be understood that the above described embodiment of my invention is for the purpose of illustration only and various changes may be made therein without departing from the spirit and scope of my invention.

I claim:

45 1. In a sealed compressor for refrigerating mechanism; an exterior sealed casing, the upper part of the casing having a cross dimension less than the lower part of the casing and the two parts being joined substantially at a flared shoulder; a main casting in the casing having a supporting portion fitted in the upper part of the casing; a compressor cylinder formed integrally with the lower end of the main casting; a vertical shaft journalled in the casting; a motor for driving the shaft having a body fixedly located within the supporting portion of the casting; an outlet for compressed refrigerant extending through and sealed into the shoulder of said casing; an inlet for refrigerant opening into the lower part of the casing; an inlet passage for the cylinder defined by a clearance between the motor body and the supporting part of the casting; and an inlet tube extending from the clearance to the cylinder, the cylinder having an inlet port opening upwardly adjacent the top surface thereof and the inlet tube having a relatively loose fit in said port for the seepage of lubricant from the inside of the casing into the cylinder.

60 2. In a sealed compressor for refrigerating mechanism; an exterior sealed casing; a casting in the casing having a supporting portion fitted in a part of the casing; a plurality of compressor cylinders each having an inlet port and each being formed as a part of the casting; a motor for

driving the compressor cylinders having a body fixedly located within the supporting portion of the casting; an outlet for the compressed refrigerant opening from said casing; an inlet for refrigerant opening into the casing; an inlet passage for each of the cylinders defined by a clearance between the motor body and the supporting part of the casting; and an inlet tube extending from each clearance to the port of one of the cylinders and having a relatively loose fit in said port for the seepage of lubricant from the inside of the casing into the cylinders.

3. In a sealed compressor for refrigerating mechanism; an exterior sealed casing having an interior space; a compressor cylinder positioned within the said casing having an inlet port; a motor for driving said compressor cylinder; an outlet means for the compressed refrigerant sealed into said casing; an inlet for refrigerant opening into the space within said casing; and

an inlet tube communicating with the space within said casing and extending to and having a relatively loose fit in said port for the seepage of lubricant from the inside of the casing into the cylinder.

WILLIAM W. HIGHAM.
